MESNE ASSIGNMENTS, TO REMINGTON RAND INC., OF NEW YORK, N. Y., A COR-
PORATION OF DELAWARE.

ACCOUNT-FINDING MACHINE.

Application filed November 8, 1920. Serial No. 422,659.

This invention relates to machines for finding accounts.

In the account finding machines described in applications Serial Number 229,996, filed 5 April 22, 1918, and Serial Number 352,601, filed January 19, 1920, now Patent No. 1,615,806, Jan. 25, 1927 (see also British Patent Number 153,844, November 2, 1920), the account cards are arranged in a tray (or 10 a series of trays) and a desired account is found by primarily locating a group of cards, secondarily locating a division or a unit of cards, and tertiary locating a card, and the finally located card is then isolated. 15 This is accomplished by providing selecting mechanism which is set by selective manipulative means comprising a series of keys so as to effect such selection.

In order to audit the accounts, audit mechanism 20 is employed as distinguished from the normal selecting mechanism which is arranged to locate and isolate a series of cards, one in each unit, so as not only to check up the system, but also find lost or misplaced accounts.

In the machine of the application referred to, a series of selectors is employed for the purpose of finding individual cards. A pair of such selectors are clutched to the actuating rock shaft by clutches so as to primarily locate the group; the selectors are then shifted along the tray to locate the division, or unit; the selectors are then moved transversely of the tray to locate the desired card; upon final location, the actuators operate to isolate or elevate only the selectors which have been previously connected therewith. In the auditing of accounts, all of the selectors are connected with the actuator while 30 additional audit selectors are interconnected with the normal selectors so as to permit a desired card in each unit to be isolated or elevated.

The clutches or controlling elements between the actuator and the respective selectors are normally under tension so that when a desired controlling mechanism is released, a desired pair of selectors will be clutched with the actuator. During auditing, all of the controlling elements are released to connect all of the selectors with the actuator. When the machine is cleared, the controlling elements are restored and again tensioned and latched in tensioned positions. Where

motor mechanism is employed to restore the 55 mechanism, undue strain will be placed on this motor mechanism when the machine is cleared and when all of the controlling elements, which have been released during the auditing operation, are restored. 60

One of the objects of this invention, therefore, is to provide an account-finding machine whereby upon clearing of the machine, the minimum strain will be thrown on the restoring mechanism or motor, so as to permit utilization of a minimum size motor. 65

Another object is to provide an account-finding machine in which the restoring mechanism is constructed and arranged to restore the selector mechanisms in succession. 70

Further objects will appear from the detail description taken in connection with the accompanying drawings, in which:

Figure 1 is a somewhat diagrammatical view of an account finding machine showing 75 the mechanism embodying this invention;

Figure 2 is a detail end elevation of Figure 1;

Figure 3 is a section on the line 3—3, Fig. 2; and

Figure 4 is a detail of the stop shown in Figure 2.

Referring to the accompanying drawings, 1 designates a tray divided by partitions 2 so as to provide a series of compartments, 85 this tray being mounted upon the body or frame work 3 of the machine. This frame has mounted thereon a carrier comprising a pair of side bars 4, which, in turn, are mounted upon the side bars 5 of a carriage. 90 The side bars 5 of the carriage are mounted for transverse movement on tracks 6 on the frame and they are arranged to carry with them the side bars 4 of the carrier which, latter in turn are arranged for longitudinal 95 movement along the carriage. Each carrier side bar carries a series of ten normal selectors 7 which are arranged for vertical movement and has also mounted thereon audit 100 selectors 8 also mounted for vertical movement. The carrier has mounted thereon a pair of actuating rock shafts 9, each of which has a series of ten clutches 10, each arranged to be clutched with its selector. Springs are provided which tend to normally 105 move the carrier to the right, Figure 1, tend to normally move the carriage side bars outwardly and normally tend to rock

the shafts 9 so as to raise the selectors; in order, however, to retain the carriage, latches 11 are provided while the carrier is retained by latches 12. These latches are controlled by keys 13 and stops are provided for arresting the carriage and the carrier in the proper positions.

In order to clutch a desired pair of normal selectors 7 with the actuator 9, through the controlling elements 10, arranged to connect the selectors with the actuator, a series of springs 14 are provided which are anchored to the frame and connect each with a bell-crank lever 15 connected in turn with a bell-crank lever 16 connected with the controlling elements. These springs, when under tension, tend to move the clutch or controlling elements 10 to the left, Figure 1, so as to clutch with the respective selectors. In order to retain the clutches out of clutching engagement, each bell-crank lever 15 is connected by a link 17 with a bell-crank lever 18 connected by a link 19 with a bell-crank 20; this bell-crank lever 20 (of which there are a series of ten) is retained by a latch 21 controlled by its proper key 13. Accordingly upon depression of the proper key, the corresponding latch 21 will be released thereby permitting the spring 14 to throw into engagement the controlling corresponding clutch elements 10 for the corresponding pair of selectors.

When it is desired to audit the accounts, the audit selectors 8 are clutched with the normal selectors by a pair of bars 22 which are shifted through a lever 23, a link 24, an arm 25, and a cross-bar 26 connected therewith, upon depression of the audit key 27. Upon the depression of this audit key, it will through the same bar 26 release all of the latches 21 and accordingly cause the springs 14 to engage all of the clutches 10 with all of the selectors 7. The auditing of the accounts can then be accomplished, all as fully described in application Ser. No. 352,601 referred to.

In order to restore the parts to normal position, restoring mechanism is provided as fully described in said application Serial Number 229,996, and British Patent, 153,344, and this restoring mechanism is of the motor mechanism type, that is, an electric motor is provided which operates through suitable mechanism upon depression of a clearing bar to clear the machine. The particular motor mechanism is fully described in an application filed of even date herewith and bearing Serial Number 422,660, now Patent No. 1,612,221, Dec. 28, 1926. It comprises in general a main motor shaft 28 having a controlling element 29 cooperating with a stop 30 connected with a line of connections to a depressible bar 31 mounted immediately adjacent the keyboard. The shaft 28 is connected with a shaft 32

which is connected by various mechanisms to the parts to be restored as fully described in application Serial Number 352,601. Accordingly when it is desired to clear the machine, the bar 31 is simply depressed which will clutch the motor through the stop mechanism with the clearing mechanisms of the machine in order to restore all parts to normal position.

During the auditing operation all of the clutch members 10 are released to cause them to engage the selectors and when the machine is to be cleared, all of the clutches and the connected mechanisms must be restored. This would throw an undue strain upon the motor mechanism since the spring 14, of necessity, is of considerable strength and as there are at least ten of these springs, their combined tension will be comparatively great and would require a motor of high horse power if all of the clutches were restored concurrently. In accordance with this invention, therefore, means is provided whereby the controlling or clutch elements are restored and tensioned in succession so as to restore the selector mechanisms not concurrently but in succession.

The shaft 32 has mounted thereon a sector 33 provided with gear teeth 34 meshing with a pinion 35 connected by a hub with an arm 36, all of which are loosely mounted on a shaft 37 in the frame. The arm 36 has mounted thereon a pair of pawls 38 held by springs 39 in engagement with a ratchet 40 fixed to the shaft 37. The ratchet 40 has a pin 41 thereon arranged to be engaged by a stop pawl 42 mounted on the frame 3. The construction is such that when the sector is moved in the direction of the arrow, Figure 3, the arm 36 and its pawls thereon are rotated in the direction of the arrows, Figure 3, so as to carry the ratchet and therefore the shaft 37 therewith, while when the direction of movement of the sector is reversed, the pawls will move idly over the ratchet which, at this time, is retained by the stop 42. The length of the toothed portion of the sector is such that during the complete movement in the direction of the arrow, Figure 3, the shaft 37 will be given a complete revolution; accordingly upon a complete oscillation of the sector, the shaft 37 will be given a complete revolution in one direction.

The shaft 37 has fixed thereto a series of ten cams 43, one for each bell-crank lever 20, and each of which cams is adapted to engage with a cam roll 44 on said bell-crank lever. These cams are arranged spirally around the shaft as shown in Figure 1, so that upon a complete revolution of the shaft 37, the bell-crank levers will be operated in succession.

Upon individual selection of any desired car, the corresponding latch 21 is released to free the corresponding bell-crank lever

20, thereby permitting the corresponding spring 14 to move the corresponding clutch 10 and connect the corresponding pair of normal selectors 7 with the actuator 9; moreover the secondary and tertiary positioning means will be thereupon actuated, as fully described in the above-mentioned patent. When the machine is to be cleared, the bar 31 will be depressed and the motor will then 10 operate through the appropriate mechanism to restore all parts back to normal positions, the corresponding cam 43 returning the corresponding bell-crank lever 20 so as to be latched by its corresponding latch 21, thereby 15 restoring the corresponding clutch and retaining it under the tension of its corresponding spring 14.

When auditing, all of the latches 21 will be released thereby causing all of the 20 clutches to be engaged. When the machine is to be cleared, the bar 31 is depressed as before; in this case, however, the cams 43 will act in succession so as by their successive engagement with the corresponding cam 25 rolls 44 on the bell-crank levers 20 to successively restore the clutches against the tension of their springs and so as to successively cause the latches 21 to latch the parts in restoring positions. In view of the fact that 30 the clutches are restored successively so that the clutch springs will be tensioned successively, the power is not thrown on the motor suddenly but gradually and the torque required will be that only to tension a single 35 spring as distinguished from the sum of those tensions. Accordingly the motor required can be of minimum size. It will, therefore be seen that in accordance with this invention a plurality of the controlling 40 elements for the selecting means are concurrently set or released, in the sense that a plurality of these elements are concurrently in a set or released position and that the restoring means is adapted and arranged to 45 restore the plurality of set or released elements in succession.

It is obvious that various changes may be made in the details of construction without departing from the spirit of this invention; 50 it is, therefore, to be understood that this invention is not to be limited to the specific details shown and described.

Having thus described the invention what is claimed is:

55 1. In an account finding machine, selecting means, a series of controlling elements therefor, actuating means for concurrently setting a plurality of said elements for cooperation with said selecting means, and means adapted to restore the set elements in succession.

2. In an account finding machine, selecting means, a series of controlling elements therefor, actuating means for concurrently 60 setting a plurality of said elements for co-

operation with said selecting means, motor mechanism, and means operated by said motor mechanism adapted to restore the set elements in succession.

3. In an account finding machine, selecting means, a series of tensioned controlling elements therefor, means for concurrently releasing a plurality of said elements, and means adapted to restore the released elements in succession. 75

4. In an account finding machine, selecting means, a series of tensioned controlling elements therefor, means for concurrently releasing a plurality of said elements, and means adapted to restore and tension the 80 released elements in succession.

5. In an account finding machine, a series of selectors, actuating means therefor, elements for connecting said selectors with said actuating means, means for concurrently setting a plurality of said elements for cooperation with said selectors, and means adapted to restore the set elements in succession. 85

6. In an account finding machine, a series of selectors, actuating means therefor, elements for connecting said selectors with said actuating means, means for concurrently setting a plurality of said elements for cooperation with said selectors, and motor mechanism adapted to restore the set elements in succession. 90

7. In an account finding machine, a series of selectors, actuating means therefor, tensioned elements for connecting said selectors with said actuating means, means for concurrently releasing a plurality of said elements in order to effect such connections, and means adapted to restore and tension the 100 released elements in succession.

8. In an account finding machine, a series of selecting means, a series of tensioned controlling elements therefor, means for retaining said elements, means for concurrently releasing a plurality of said retaining means, and means for restoring and tensioning the 105 released elements in succession.

9. In an account finding machine, selecting means, a series of tensioned controlling elements therefor, means for retaining said elements, means for concurrently releasing 110 a plurality of said retaining means, and means adapted to successively tension and restore the released elements to be retained by said retaining means.

10. An account finding machine having 115 selecting means and a series of selector mechanisms and means for concurrently setting a plurality of said mechanisms for cooperation with said selecting means, characterized by means adapted to restore the set mechanisms 120 in succession.

11. An account finding machine, having selecting means and a series of selector mechanisms and means for concurrently setting 125 a plurality of said mechanisms for coopera- 130

- tion with said selecting means, characterized by motor mechanism adapted to restore the set selector mechanisms in succession.
12. An account finding machine having a series of tensioned selector mechanisms and means for concurrently releasing a plurality of said mechanisms, characterized by means adapted to restore and tension the released mechanisms in succession.
- 10 13. An account finding machine having a series of tensioned selector mechanisms and means for concurrently releasing a plurality of said mechanisms, characterized by motor mechanism adapted to restore and tension the released selector mechanisms in succession.
14. An account finding machine having selecting means and a series of selector mechanisms and actuating means adapted at will 20 to concurrently set one or a series of said mechanisms for cooperation with said selecting means, characterized by means for restoring the set mechanisms, adapted to restore a series of said mechanisms in succession.
15. An account finding machine having selecting means and a series of selector mechanisms and actuating means for concurrently setting a plurality of said mechanisms for 30 cooperation with said selecting means in order to audit the accounts, characterized by
- means adapted to restore the set mechanisms in succession.
16. An account finding machine having a series of selector mechanisms and means adapted at will to set one of said mechanisms in order to find an individual account, or to concurrently set a series of said mechanisms in order to audit the accounts, characterized by means for restoring said mechanisms, adapted to restore a series of the set mechanisms in succession.
17. An account finding machine having a series of individual selectors, audit selectors, and actuating means for concurrently setting a plurality of said selectors into operative position, characterized by means for restoring said selectors, adapted to restore the set individual selectors in succession.
18. An account finding machine having a series of individual selectors, audit selectors, and actuating means for concurrently setting a plurality of said selectors into operative position, characterized by motor mechanism for restoring said selectors, adapted to restore the set individual selectors in succession.

In testimony whereof we affix our signatures this 22nd day of Sept., 1920.
